UNITED STATES PATENT OFFICE

148,398

DESIGN FOR A DISPENSER CABINET OR THE LIKE

Aubrey C. Swygard, Bryan, Ohio, assignor to The Aro Equipment Corporation, Bryan, Ohio, a corporation of Ohio

Application January 31, 1946, Serial No. 126,117

Term of patent 7 years

(Cl. D52—2)

To all whom it may concern:

Be it known that I, Aubrey C. Swygard, a citizen of the United States and a resident of Bryan, in the county of Williams and State of Ohio, have invented a new, original, and ornamental Design for a Dispenser Cabinet or the like, of which the following is a specification, reference being had to the accompanying drawing, forming a part thereof.

Figure 1 is a perspective view of a dispenser cabinet or the like showing my new design; and

I claim:

The ornamental design for a dispenser cabinet or the like, substantially as shown.

AUBREY C. SWYGARD.
